UNITED STATES PATENT OFFICE

JOSEPH R. FRANK, OF HOLLIS, NEW YORK, ASSIGNOR TO THE TEFRA CO., OF STAMFORD, CONNECTICUT, A CORPORATION OF DELAWARE

TOOTHBRUSH

Application filed June 26, 1930. Serial No. 464,025.

My invention relates to toothbrushes and particularly to the type of brush shown and described in United States patent to Booty No. 1,592,292 granted July 13, 1926. It is the 5 object of my invention to provide an improved form and arrangement of parts for increasing the strength of the grip of the loop upon the tufted head of the brush of said Booty patent, whereby the head may be more 10 securely held in position during the use of the brush but without in any way detracting from the adaptability of the brush with respect to the substitution of a new brush head for the old one when such old brush head becomes 15 worn. It is one of the objects of my invention to provide means for adjusting the effective size of the loop whereby it shall not be necessary to employ exceedingly great nicety in the manufacture of the parts, my improved 20 arrangement making possible an adjustment of the loop to standard size regardless of any slight original deviation from such standard size.

It is another object of my invention to improve devices of this type in sundry details hereinafter pointed out. The preferred means by which I have accomplished my several objects are illustrated in the drawings and are hereinafter specifically described. 30 That which I believe to be new and desire to cover by Letters Patent is set forth in the claims.

In the drawings,—

Fig. 1 is a face view of the end portion of 35 the handle of my improved brush, being shown upon an enlarged scale;

Fig. 2 is a side view of my improved brush, showing the brush head in position in the loop shown in Fig. 1;

Fig. 3 is a view similar to a portion of Fig. 1 but showing certain of the parts in section; and

Fig. 4 is a vertical cross sectional view taken at line 4—4 of Fig. 1.

Referring to the several figures of the drawings, in which corresponding parts are indicated by the same reference characters, 10 indicates a handle formed of pyralin or other non-metallic material. Upon the end of the 50 handle 10, I have provided a loop 11 which is

closed about its entire periphery except for an opening therein at one end portion provided by a slot 12 extending into the body of the handle 10 longitudinally thereof. In the construction shown, the loop 11 comprises a 55 band portion 13 and a flange portion 14 at one edge of the band, the band 13, the flange 14, and the body portion 10 of the handle having, in the finished article at least, an integral formation with each other.

A brush head 15 provided with tufts of bristles 16 is secured in position in the loop 11, having such a fit within the loop as to place the same under tension longitudinally of the band 13. By the use of this construction the head 15 is held very securely in position under hard conditions of use of the brush without danger of the brush head being accidentally displaced from the loop, when the loop and head are given the desired relative 70 size with respect to each other. At the same time, the arrangement is such that when it is desired the brush head can be removed readily and quickly from the loop by pressure upon the brush head between the spaced 75 flanges 14.

For insuring a proper fit of the loop 11 about the brush head 15, I have provided means for adjusting the effective size of the loop, such adjusting means being so arranged 80 as to be effective for its purpose and so as to be at the same time unobjectionable from the standpoint of the user of the brush. This adjusting means in my improved construction comprises a screw threaded pin or bolt 85 17 which is entirely confined within openings through the portions of the handle at opposite sides of the slot 12 adjacent to the end of the loop 11. The bolt 17 has its head portion 18 loosely mounted in a suitable opening in the handle portion at one side of the slot 12, while the opposite end portion of the bolt has screw-threaded engagement with an opening through the handle portion at the opposite side of the slot, whereby the bolt 90 acts as a tie across the slot for limiting outward movement of the opposite side portions of the loop.

By the use of my improved construction, after the parts have been prepared with only 100

ordinary care upon a commercial basis, I am enabled by adjusting the screw 17 to adjust the effective size of the loop 11 so as to make it capable of having effective gripping engagement with a brush head 15 of standard size. By this arrangement, I am also enabled to effect a second adjustment if necessary to make the loop effective with brush heads slightly smaller than the standard size. Furthermore, in case a loop should be stretched slightly by long continued use, a user is enabled by a very slight adjustment of the screw 17 to effect the necessary tightening of the loop so as to make it effective for continued use. With the bolt 17 tightened to its proper adjustment for cooperation with a given brush head, the slot 12 is still effective for providing a certain amount of yielding action for preventing breakage when the brush head is forced into position. The open end of the slot at the right of the bolt in Figs. 1 and 3 yields to a certain extent, and even the part of the slot at the left of the bolt in said figures makes possible a limited swinging movement of the side portions transversely of the loop by which my desired results are obtained.

While I prefer to employ the construction substantially as shown in my drawings, it is to be understood that my invention is not limited to such construction except so far as the claims may be so limited by the prior art.

I claim:—

- 35 1. A toothbrush comprising a handle formed of non-metallic material, a loop also formed of non-metallic material on the end of said handle closed about its entire periphery except for an opening therein provided by a slot extending into the body of the handle longitudinally of the handle, a tufted brush head adapted substantially to fit said loop, and means adjustable transversely of the loop in fixed position longitudinally of the handle and the loop for partially closing said slot for causing the loop tightly to grip said head, said adjustable means being disposed completely between the outer side faces of the portions at opposite sides of the slot.
- 40 2. A toothbrush comprising a handle formed of non-metallic material, a loop on the end of said handle closed about its entire periphery except for an opening therein provided by a slot extending into the body of the handle longitudinally of the handle, a tufted brush head adapted substantially to fit said loop, and a threaded bolt confined completely within openings extending through the handle portions at opposite sides of the slot adjacent to the loop for pressing said handle portions toward each other for causing the loop tightly to grip said head.
- 45 3. A toothbrush comprising a handle formed of non-metallic material, a loop on the end of said handle closed about its entire

periphery except for an opening therein provided by a slot extending into the body of the handle longitudinally of the handle, a tufted brush head adapted substantially to fit said loop, and tie means extending across the slot and within the limits of the slot serving to limit outward movement of opposite side portions of the loop for causing it tightly to grip said brush head, said tie means being disposed completely between the outer side faces of the portions at opposite sides of the slot.
